DESIGN FOR A LINK CHAIN FOR A BRACELET OR SIMILAR ARTICLE

George E. Fournier, Pawtucket, R. I.

Application May 16, 1946, Serial No. 129,737

Term of patent 14 years

(Cl. D45—4)

To all whom it may concern:

Be it known that I, George E. Fournier, a citizen of the United States, residing at Pawtucket, in the county of Providence, State of Rhode Island, have invented a new, original, and ornamental Design for a Link Chain for a Bracelet or Similar Article, of which the following is a specification, reference being had to the accompanying drawing, forming part thereof.

Fig. 1 is a top plan view of a link chain showing my new design;

Fig. 2 is a side elevational view of the link chain;

Fig. 3 is a sectional view of the link chain taken on line 3—3 of Fig. 1;

Fig. 4 is a sectional view taken on line 4—4 of Fig. 1; and

Fig. 5 is a perspective view of one of the links.
I claim:

The ornamental design for a link chain for a bracelet or similar article, as shown.

GEORGE E. FOURNIER.
